ATTORNEY

UNITED STATES PATENT OFFICE

PETER D. JOHNSON, OF FORT DODGE, IOWA

BARREL HEAD SETTING MACHINE

Application filed November 12, 1930. Serial No. 495,207.

This invention relates to certain new and useful improvements in barrel head setting machines which embodies among other characteristics means for yieldably guiding the barrel head in position for use.

Another object of the invention consists of a machine of this character having a treadle operated mechanism for projecting the barrel heads through the expansible guide.

10 More specifically stated the guide is provided with a support for the barrel or other vessel to which the heads are applied.

With the above and other objects in view, the invention further consists of the following novel features and details of construction, to be hereinafter more fully described, illustrated in the accompanying drawings and pointed out in the appended claim.

In the drawings:

20 Figure 1 is a sectional view taken through the invention illustrating by full and dotted lines the respective positions of the barrel head before and after the machine is set in operation.

25 Figure 2 is a view similar to Figure 1 showing the machine in elevation.

Figure 3 is a top plan view of the invention with the barrel removed.

Figure 4 is a detail view illustrating the 30 manner of connecting the retractile springs of the sections with the studs.

Referring to the drawings in detail wherein like characters of reference denote corresponding parts, the reference character 10 indicates generally a base or platform having an opening 11 for the accommodation of a disk member 12. A support, such as indicated at 13, arranged beneath the base or platform 10 adjacent the opening 11 therein, 35 is designed for engagement with the under side of the disk 12 whereby the upper surface thereof may be aligned with that of the corresponding surface of the platform or base.

The adaptor ring generally designated as 40 at 14, is composed of sections 15 of arcuate formation having skirts or flanges 16 downwardly and outwardly projecting from the lowermost edges thereof. Angle bars 17, arranged upon the outer sides of each of the 45 sections 15 and shaped in conformity thereto,

terminate to provide apertured ears 18 for the accommodation of headed studs 19. Retractable springs 20 are designed for connection at the ends thereof with the confronting extremities of immediate stud bolts whereby the sections of the adaptor ring will be normally held contracted.

As obviously apparent from the illustrations of my invention in Figures 1 and 2 of the drawings, the upper flanges of the angle plates 17 provide a support for the adjacent periphery of the barrel, tub or other form of receptacle. The upper surfaces of the angle plates 17 are disposed below the uppermost edges of the sections 15 whereby the latter will project an appreciable distance within the receptacle in order that the projection of the barrel head within the barrel may be regulated.

Fixed and shiftably mounted L-shaped plates 21 and 22 respectively, arranged in the manner shown, are mounted upon supports 23 elevated from the platform 10 and yieldably spaced apart by compression springs 24 interposed therebetween. Attaching flanges 25, carried upon the extremities of the shiftably mounted L-shaped plates 22, are secured with appropriate portions of the skirts or flanges 16 of the several sections 15 whereby additional spring tension will be exercised upon and between the several sections of the guide ring to normally hold the sections in a contracted state.

A fulcrum lever 26, pivotally mounted, as at 27, upon the support 13, is bifurcated to provide arms 28 journaly associated with a bar 29 horizontally suspended between legs 30 depending from the disk 12 through the support 13. A foot pedal 31, carried upon the upstanding end of a link 32, is pivotally connected at its opposite end with the remaining extremity of the fulcrum lever 26 whereby depression of the foot pedal 31 and the link 32 will cause the disk 12 to occupy an elevated position whereby the barrel head, such as indicated at 33 in Figure 1 of the drawings, will be shifted from the full to the dotted line position. Skirts 16, formed upon each of the several sections of the guide ring, will cause the barrel head to be guided

centrally through the adaptor. At all times during the forcing of the barrel head through the guide ring, the spring tension will be in a direction opposed to that of the spreading action of the barrel head whereby undue flexing of the barrel, tub or other receptacle will be prevented and a tighter fitting between the receptacle and head facilitated.

Although I have shown all of the sections with the exception of one provided with the movable and stationary L-shaped members, it is obviously apparent that such could be employed at will without departing from the spirit of the invention.

15 The invention is susceptible of various changes in its form, proportions and minor details of construction and the right is herein reserved to make such changes as properly fall within the scope of the appended claim.

20 Having described the invention, what is claimed is:

A barrel head setting machine comprising a ring formed of sections each having inclined and straight guiding portions, yieldable means connecting said sections to normally hold them in contracted position within a barrel body, angle bars carried by and shaped in conformity to the sections for supporting a barrel thereon with its edge below and in spaced relation to the upper periphery of the ring, stationary and movable L-shaped plates positioned adjacent said sections, spring means yieldably forcing the L-shaped plates apart to hold the ring contracted, a disk arranged beneath the ring carrying a barrel head thereon, and an operating mechanism having connection with said disk to shift the latter and the barrel head through the guiding portions of the ring and in alignment with the head receiving croze in the barrel body.

In testimony whereof I affix my signature.

PEDER D. JOHNSON.
